(57) **CLAIM**

We claim the ornamental design for a control device, as shown and described.

DESCRIPTION

FIG. 1 is perspective view of a control device showing our new design.

FIG. 2 is a front view thereof.

FIG. 3 is a left side view thereof.

FIG. 4 is a right side view thereof.

FIG. 5 is a top view thereof; and,

FIG. 6 is a bottom view thereof.

The rear views form no part of the design and are omitted. The portions of the drawings appearing in broken lines are for environment only and do not form part of the claimed design.

1 Claim, 4 Drawing Sheets

Related U.S. Application Data

continuation of application No. 29/472,772, filed on Nov. 15, 2013, now Pat. No. Des. 734,277.
